UNITED STATES PATENT OFFICE.

LOUIS E. ARMSTRONG, OF FORT DODGE, IOWA, ASSIGNOR TO PLYMOUTH GYPSUM COMPANY, OF FORT DODGE, IOWA, A CORPORATION OF IOWA.

PLASTER BOARD.

Application filed July 31, 1922. Serial No. 578,630.

To all whom it may concern:

Be it known that I, LOUIS E. ARMSTRONG, a citizen of the United States, and a resident of Fort Dodge, in the county of Webster and 5 State of Iowa, have invented certain new and useful Improvements in Plaster Board, of which the following is a specification.

This invention relates to improvements in plaster board, and more particularly to that 10 class of plaster board provided with a covered or sealed edge, whereby a more finished product is obtained.

The object of the invention is to provide a new and useful construction for plaster 15 board embodying a novel treatment of the edges whereby a more uniform and perfect sealing is attained, and smoother and stronger edges are produced.

The construction and method of manufacture are clearly set forth in the following 20 description, reference being had to the accompanying drawings, wherein,

Figure 1 is a perspective view of a fragment of plaster board with portions of the 25 covering sheets folded back in order to more clearly reveal the construction,

Figure 2 is an enlarged cross-sectional view of the board as taken on line 2—2 of Figure 1, and

30 Figure 3 is a view of a fragment of the edge forming strip, showing the arrangement of the perforations.

Plaster board is a well known building 35 material consisting of a relatively thin layer of plaster or stucco interposed between layers or sheets of tough paper. It is manufactured by a process whereby the wet plaster is fed between the sheets and rolled to the desired uniform thickness and cut into 40 lengths of convenient size for handling, and finally dried. The sealing or binding of the edges forms a part of the manufacturing process, whereby the side or longitudinal edges of the board are covered with paper, 45 thus entirely enveloping the plaster within its covering.

The plaster board herein illustrated is 50 typical of the product in its general formation, consisting of the layer or body of stucco 1 interposed between the covering sheets 2—2 of paper, or other fibrous material, a tough grade of paper, however, being the common material used for this purpose. The cover sheets 2—2 (which need not be identi-

fied as the top or bottom sheet, inasmuch as 55 the board is alike on both sides) are of the same width as the finished board, their edges terminating flush with the edges of the body 1. Extending along the edges of the body 1 are separate and relatively narrow strips 60 3—3 of the same material as the cover sheets, which are readily seen to be folded over both edges in U-shape, with their marginal portions extending beneath the marginal portions of the cover sheets 2—2. 65

Considering one of these strips, Figure 3, the same is adapted to be folded during the manufacture of the board, into a comparatively narrow central portion 4, included between parallel fold lines 4^a—4^a, and two 70 relatively wider marginal portions 5—5. Throughout the marginal portions 5—5 are equidistantly spaced holes or perforations 6 of relatively large diameter, although the size, number and arrangement of these perforations is not material. Where comparatively large perforations are used, however, they are preferably arranged in staggered 75 relation on opposite sides of the central portion 4, in order that they will not register 80 with each other when the strip is incorporated into the board. The reason for this will be presently pointed out.

In the finished board, this strip 3 extends 85 along the edge of the board, the central portion 4 forming the edge face, and the marginal portions 5—5 being overlapped by the marginal portions of the cover sheets 2—2. The perforations 6—6 afford a means of sealing 90 the overlapping marginal portions of the sheets 2—2, and strip 3, by utilizing the adhesive properties of the stucco. Thus in the passage of the board through the pressing rolls of the machine, the wet stucco passes 95 through the perforations, adhering to the exposed under surface of the cover sheets, thereby forming a bond securely sealing the covering material along the edges of the board.

The advantages of a construction such 100 as herein disclosed are numerous. The strip 3 completely encloses the margin of the body 1, thus providing a neat, regular and uniform edge. It further makes a clean edge; that is, an edge that is not impaired 105 by quantities of plaster which would otherwise be squeezed out between the edges of the covering sheets, and deposited upon
